BERT CHAPMAN, OF ENDICOTT, NEW YORK, ASSIGNOR TO INTERNATIONAL TIME RECORDING COMPANY OF NEW YORK, OF ENDICOTT, NEW YORK, A CORPORATION OF NEW YORK

CLOCK RESETTING DEVICE

Application filed May 14, 1927. Serial No. 191,297.

This invention relates to clocks and more particularly to a resetting device for resetting clocks to a predetermined starting position.

5 For the purpose of clearly disclosing my invention I have shown it as applied to a secondary clock, or in other words a clock which is controlled electrically by a master clock.

10 An object of my invention is to provide an improved and simplified means by which a clock may be reset to a predetermined position.

Another object is to provide a device by 15 which a clock may be reset to a predetermined position upon a single operation of the resetting means or if the clock has been running for more than a given time two or more strokes may be employed to quickly 20 return it to its normal position.

Other objects and advantages of my invention will be obvious from the following particular description embodying the invention or from an inspection of the accompanying 25 drawings.

Fig. 1 is a rear elevational view of a secondary clock with my resetting means connected thereto.

Fig. 2 is a rear elevational view of the 30 resetting mechanism in an operating position.

Fig. 3 is a detail view of a latching device.

Fig. 4 is a rear elevational view of a secondary driving mechanism without the clock 35 face.

Fig. 5 is a detail showing the connection between the clock and restoring mechanism.

Fig. 6 is a side elevational view of a secondary clock with my device attached.

40 An understanding of the nature and purpose of my invention may easily be derived from the following specific example. Clocks with resetting means are particularly adapted to hospitals where timing is a great factor.

45 The usefulness of such a clock is especially adapted in taking pulse beats, temperatures, etc., also for timing purposes in an operating room. When the temperature or pulse beat of a patient is to be taken by the doctor,

50 simultaneously with the starting of the tak-

ing of a pulse beat he pulls down a chain, handle or some other means which will return the clock to a predetermined position. The dial of the clock instead of having numerals pertaining to hours and minutes will bear information pertaining to seconds and minutes, that is, each actuation that the clock receives will step the hand around one second. Assuming now that the clock has been reset, the doctor will continue to count the pulse of the patient until the clock designates a certain number of seconds. If he also desires to take the temperature of the person, he will again pull the chain or handle in a downward direction which will reset the clock to a predetermined position and likewise the clock will disclose the elapsed time in minutes and seconds. It is therefore obvious that my device has unlimited uses, not only in hospitals but also may be used in 70 laboratories or any place where timing is a factor.

Referring more particularly to Fig. 4 the operation of the secondary used in conjunction with my resetting mechanism will be described.

The motor power for actuating the secondary unit comprises a magnet 10 mounted in the well known manner in a bracket 11. The magnet 10 coacts with an armature 12 pivoted at 13 and held away from the cores of the magnet by a spring 14. Energization of the magnet 10 actuates the arm 12 which has fixed thereto an arm 15 on which is pivotally mounted at 16 an actuating pawl 17. This pawl normally rests in one of the notches of the ratchet wheel 18 and as soon as the armature 12 is actuated by the magnet 10 the pawl moves to the right and engages in the next or adjacent notch at 18'. Upon de-energization of the magnet 10 the armature 12 returns to its normal position under the influence of the spring 14 rotating the ratchet wheel 18 the distance of one notch. A retaining pawl 19 (Fig. 2) biased by a spring 20 is provided to hold the ratchet wheel 18 in the position to which it has been turned by the actuating pawl 17. Associated with the ratchet wheel 18 is the usual clock mechanism including reduction gearing, etc., for 100

operating the hands 21 and 21' (Fig. 6) respectively.

Reference will now be had to Figs. 1, 2, 3, 5 and 6 for a detailed description of the resetting device. As disclosed in Fig. 2 my mechanism comprises a support plate 22 which is fixed in the well known manner by screws 22' to a secondary clock as viewed in Fig. 1. The shaft 22a of the secondary clock has fixed thereon at its forward end a seconds hand 21 and carries loosely a sleeve 21a which in turn has fixed thereto a minute hand 21'; the hands being geared for operation at the proper ratios by the reduction gearing referred to. Rigidly fixed to the rear end of the shaft 22a by means of a set screw 23 is a sleeve 24. Adjacent to the sleeve 24 and rotatably mounted on the end of the shaft 22a is a pinion gear 25, retained thereon by means 10 of a screw 26 inserted in the end of the shaft. Surrounding the shaft 22a is a helical spring 27 anchored at its opposite ends to the sleeve and pinion gear at 28 and 29 respectively. By means of the spring 27 a flexible connection is made between the pinion 25 and the shaft 22a. Pivotal mounted by means of a screw 30 to the left side of the support plate 22 as viewed in Figs. 1 and 2 is a ratchet wheel 31 and a plate member 32. The plate member 32 includes a cam surface 33, an arm 34 and two lips 35 and 36, respectively. A stepping pawl 37 having two rearward extensions 39 and 40 is pivoted at 38 to the arm 34. One of the rearward extensions 39 carries a chain 41 for engaging the stepping pawl 37 between the notches 43 of the ratchet wheel 31 for actuating the resetting device and the other extension 40 is biased by a spring 42 for disengaging the pawl from between the notches 43 of the ratchet wheel 31 when the chain is released. Integral with the arm 34 on the plate member 32 is a stop 49b which coacts with the extension 39 of the stepping pawl 37 when the pawl is returned to normal position (Fig. 1) by the spring 42.

When the chain 41 is pulled from the position shown in Fig. 1 to that of Fig. 2, the plate 32 is rotated about its pivotal point 30 until the lip 36, acting as a limit stop, abuts the surface 50 of the frame 22. Simultaneously with the releasing of the chain 41 the plate 32 by means of a spring 44 connected to the plate and frame at 45 and 46 respectively will return the plate to its normal position. A stop 47 is provided so that when the lip 35 comes in contact with the stop, plate 32 will be held in the position as viewed in Fig. 1. Prior to the lip 35 coming in contact with the stop 47 the other lip 36 will strike the tail 48 of an arm 49 rotatably mounted at its upper end on the pin 30. Also mounted on the pin 30 through a slot connection 52 is another arm 49'. The lower end 65 of the arm 49' carries a pin 51 engaging in

a slot 53 in the arm 49. Fixed on the clock actuating wheel 18 is a stud 54 which coacts with a latching portion 56 of the arm 49' as viewed in Fig. 3. Each time the actuating wheel 18 makes a complete revolution in a clockwise direction, the stud 54 engages with the latch 56. Integral with the arm 49 is a member 57 which abuts against the surface 58b of the frame 22 when the mechanism is actuated to the position shown in Fig. 2, the lip 36 releasing the tail 48 permitting spring 59a to move the parts to this position. In the normal position of Fig. 1 with the lip 36 cooperating with the tail 48 the arms 49 and 49' are held in their inoperative positions 80 away from the stud 54.

A cam follower 58 having two lifting members 59 and 60 respectively is pivotally mounted to the support plate 22 at 57. A holding pawl 19 biased by spring 20 and having a pin 64 fixed thereon is provided for holding the actuating wheel 18 to the position to which it has been actuated by the stepping pawl 17. The purpose of pin 64 will be described presently. 90

When the arm 34 is pulled from the position of Fig. 1 to that of Fig. 2 by the chain 41, the cam follower 58 will rise from the position shown in Fig. 1 onto the surface of the cam 33 as shown in Fig. 2. Simultaneously when the cam follower 58 begins to rise from its lower position onto the surface of the cam 33, the lifting members 59 and 60, respectively, will lift the actuating pawl 17 and holding pawl 19 upwardly out of engagement with the actuating wheel 18 as viewed in Fig. 2, allowing the wheel 18 to be turned in a backward or clockwise direction through the ratchet wheel 31 and coacting pinion gear 25 to its normal position. 100

Reference will now be had to Figs. 1 and 2 for a general description of the operation of my device. As is well known the secondary movement of a clock is actuated intermittently from a master clock. The impulses for actuating the secondary vary but in this specific case the clock will receive an impulse every second. As previously mentioned we will assume the clock to be installed in a hospital and a doctor wants to take the pulse 115 beat of a patient. He will pull the chain 41 from the position shown in Fig. 1 to that in Fig. 2. The actuation of this chain will cause the stepping pawl 37 to engage in one of the notches 43 of the ratchet wheel 31 and simultaneously pull the plate member 32 to the position shown in Fig. 2. The pinion 25 meshing with the ratchet wheel 31 obviously will also be rotated and will in turn rotate the shaft having the minute and seconds hands mounted thereon returning them to normal position. In other words, when the ratchet wheel is moved in a counterclockwise direction the pinion gear 25 is moved in a clockwise direction as viewed in Fig. 1. When 130

the plate 32 starts its downward movement, the cam follower 58 will rise upon the periphery of the cam 33 and simultaneously lift the actuating pawl 17 and holding pawl 19 out of engagement with the actuating wheel 18 by 5 means of the lifting members 59 and 60, respectively, allowing the actuating wheel through the ratchet 31 and pinion gear 25 to be rotated. The actuating wheel 18 will be allowed to rotate one complete revolution at 10 which time the stud 54 will be latched by the latching member 56. Normally the spring 59a holds the arm 49' to the right of the position shown in Fig. 3. When the stud 54 strikes the latch shoulder 56 it moves the shoulder and the arm 49' to the position shown in Fig. 3 against the action of spring 59a, this yielding serving to absorb the shock of the impact. Also as the stud 54 approaches 15 the latch shoulder 56 it engages the upper surface of the arm 49 camming the latter downwardly until the stud 54 passes beyond the shoulder 49a integral with the arm 49. This shoulder then springs back to the position of Fig. 3 to prevent rebound action of the actuating wheel 18. When 20 the device is returned to its normal or inoperative position by releasing the chain 41 as shown in Fig. 1, the cam follower 25 58 will slide off the periphery of the cam 33 allowing the actuating pawl 17 and holding pawl 19 to engage the ratchet wheel 18. The plate member 32 through the medium of a spring 44 will also be returned to normal 30 position. The purpose of the yielding connection shown in Fig. 5 is to permit the chain 41 to be pulled to its limit, thereby actuating the clock mechanism including the pinion gear 25 also to its limit after the clock 35 mechanism and the sleeve 24 have been locked 40 in their normal positions. It will also be observed that if the pawl 19 is not immediately withdrawn from engagement with the teeth of the ratchet wheel 18, that the spring 45 27 will be wound until such time when sufficient movement has been given to the camming plate 58 to effect the proper disengagement of the pawl 19 from the teeth of the ratchet wheel 18. 50 Viewing the dial as seen from the back in Fig. 1 the long hand 21 is the seconds hand and the graduations are in increments of one second. Each impulse of the clock steps the second hand 21 one graduation or one second. 55 A complete rotation of this hand thus represents one minute. The minute or small hand 21' when in the position shown in Fig. 1, presuming that this hand is geared to the seconds hand on a 12 to 1 ratio, will represent 60 an elapsed time of one minute. One complete stroke of the restoring mechanism is adapted to restore the seconds hand 21 one complete revolution or one minute. Obviously, if the clock has run for several minutes the minute 65 or small hand 21' will register with 10, 15 or 20, etc., and to return this hand to zero position will require several actuating and restoring strokes of the restoring mechanism. 70 The actuating pawl 17 has a projecting arm 66 adapted to engage a stop arm 67 adjustably attached by means of a screw and slot connection to the front plate 68 of the clock. A leather or other suitable washer 69 may be fastened to the stop arm 67 to absorb the shock and to reduce the noise. In order to further 75 insure quietness of the device, a toggle joint 70 is provided between the armature 12 and the frame member 71 having a spring 72. When the magnet 10 is energized and the armature moves into contact with ratchet 18 80 the spring 72 on the toggle will tend to hold back against the action of the magnet and thus ease the shock with which the armature strikes the ratchet. 85 While I have shown and described and pointed out the fundamental novel features of the invention as applied to a single modification it will be understood that various omissions and substitutions and changes in the form and details of the device illustrated and in its operation may be made by those skilled 90 in the art without departing from the spirit of the invention. I intend to be limited therefore only as indicated by the scope of the 95 following claims. 100 What is claimed is: 1. In an indicating device, an index, means for imparting step by step operating impulses to said index for actuating the same, a gear having a resilient connection with said index, an actuating pawl adapted to be brought into cooperation with said gear for actuating the same, means for actuating said pawl into cooperation with said gear and means for restoring the pawl to a normal or predetermined position. 105 2. In a clock mechanism, an index, means for actuating said index, a gear rotatable with said index for driving the same to restore said pointer to a predetermined position, an actuating pawl brought into operation for actuating said gear, means for actuating said pawl into cooperation with said gear, means for stopping the index in a predetermined restored position, means for preventing rebound of the index and means for returning the actuating pawl to normal or predetermined position. 110 3. In a clock mechanism, an index pointer, means for actuating said index, a pawl for retaining said pointer in actuated position, means for shifting said pawl thereby releasing the pointer to permit the pointer to return to normal position, means for stopping the index pointer in a predetermined restored position, means for preventing rebound of the pointer, means for maintaining the stopping means and rebound preventing means normally in inoperative position, and means 115 brought into operation during the restoring 120 125 130

operation for moving the stopping and rebound preventing means into operative position.

4. In a clock mechanism, an index pointer, 5 means for actuating the index pointer, means comprising a pawl for retaining the index pointer in actuated position, means consisting of a manually operated plate, a pawl carried by the plate, a gear engaged by the 10 pawl having connections to drive said pointer for restoring the latter, and means controlled by the manually operated plate for releasing the pawl.

5. In an indicating device having an index 15 and a train of mechanism for imparting step by step operating impulses to said index for actuating the same, in combination a gear associated with said index for restoring the same, an actuating pawl normally out of engagement with the teeth of said gear and adapted to be shifted into engagement with said gear teeth for actuating the gear and means for shifting said pawl into engagement with the teeth of said gear and for 25 actuating said pawl.

6. In a clock mechanism having an index pointer and means for driving said index pointer to indicate elapsed time by its position with respect to a normal starting position, 30 a device adapted to be reciprocated to effect restoration of the index pointer to its normal starting position, an index pointer rebound preventing means, spring means whereby the rebound preventing means is rendered effective during the movement in 35 one direction of the restoring device, and means under control of the restoring device for rendering the rebound preventing means ineffective during the movement of the restoring device in the other direction.

In testimony whereof I hereto affix my signature.

BERT CHAPMAN.
